UNITED STATES PATENT OFFICE.

CHARLEY H. WILLIAMSON, OF BLISSFIELD, OHIO.

MEANS FOR UNLOADING GRAVEL.

No. 820,538.

Specification of Letters Patent.

Patented May 15, 1906.

Application filed October 13, 1905. Serial No. 282,636.

To all whom it may concern:

Be it known that I, CHARLEY H. WILLIAMSON, a citizen of the United States, residing at Blissfield, in the county of Coshocton and 5 State of Ohio, have invented certain new and useful Improvements in Means for Unloading Gravel, of which the following is a specification.

The object of my invention is to provide 10 an improved unloading device for cars, especially adaptable for gravel-cars, and designed to provide improved automatic means whereby the discharge of the gravel may be regulated, so that the gravel may be deposited 15 either between the tracks or outside the same.

The invention consists, essentially, of a 20 gravel-car provided on its bottom with a tilting section closing the discharge-opening and also provided with two adjustable plows, the 25 parts being so arranged that the tilting section will be unlocked and tilted to allow the gravel to discharge from the car, while at the same time the plows may be adjusted to cause the gravel to be deposited either 30 between the tracks or outside the tracks.

More specifically, the invention consists of 35 a normally locked tilting section in the bottom of the car, a plunger or locking device designed to be drawn into engagement with the tilting section to both unlock and tilt the same, and two adjustable plows mounted side by side to move with the plunger for the purpose of scraping the gravel in a direction 40 between the tracks or outside of the tracks, said plows being provided with means whereby their angular forward ends may be adjusted toward or away from each other, so as to produce a scraper that will deflect the gravel either toward the middle of the track 45 between the rails or outside the latter.

For a full description of the invention and 50 the merits thereof and also to acquire a knowledge of the details of construction of the means for effecting the result reference is 55 to be had to the following description and accompanying drawings, in which—

Figure 1 is a plan view illustrating two flat 55 cars provided with the improved unloading mechanism of my invention. Fig. 2 is a vertical longitudinal section taken through the cars and through the unloading mechanism. Fig. 3 is a perspective view, on an enlarged 60 scale, illustrating the door-unlocking plunger and scraping-plows. Fig. 4 is a bottom perspective of the tilting section of the car-

bottom designed for actuation by the plunger illustrated in Fig. 3. Fig. 5 is a fragmentary view illustrating the action of the plunger with respect to the tilting section. 60

In the bottom 1 of the car is mounted a tilting section 2, which is journaled, preferably, on a rod 3, to swing about its longitudinal axis and which is designed to close the bottom discharge-opening 4 of the car. The 65 bottom or floor of the car is provided on its outer side with a keeper 5, with which a latch 6 is designed to be interlocked, and said latch is mounted on the tilting section 2 and is connected by a rod 7 to one end of a lever 8. 70 The lever 8 is fulcrumed at 8^a on the bottom of the tilting section 2 and is guided thereon by a slot-and-pin connection 8^b and has one end projecting in front of a curved recess 9. In the recess 9 is mounted a roller 10, as best 75 shown in Fig. 4.

For the purpose of automatically unlocking the tilting section 2 and swinging it around to an open vertical position I have provided a plunger or unlocking device 11, 80 which is provided with a cam-surface 12 at its front end and is drawn forwardly by means of a cable 13, actuated, preferably, by the engine, whereby it may be drawn forwardly. In the forward movement of the 85 plunger or unlocking device 11 its cam-surface or nose first comes into contact with the lever 8 and rocks the latter, thereby drawing the rod 7, carrying the latch 6, and disengaging the latter from the keeper 5, so as to unlock the tilting section 2. The continued 90 forward movement of the plunger 11 causes its nose 12 to ride over the roller 10 and against the wall of the recess 9, which acts as a cam-surface in connection with the nose 12, 95 and this action, as will be evident from Fig. 5, will cause the said section 2 to tilt to an open position and allow the load of gravel to partly discharge through the opening 4.

To provide for the distribution of the 100 gravel that remains on the floor of the car, I employ two spaced-apart adjustable plows 14, which are secured to a frame consisting of longitudinal beams 15 and cross-beams 16. The plows 14 are hinged at one rear edge, as 105 shown at 14^a, so as to swing in a horizontal plane over the floor of the car, and they are provided at their front ends with angular scraping portions 17, as shown best in Figs. 1 and 3. The two angular portions of the 110 plows are preferably connected together by braces 17^a. The plows 14 are connected by

links 19 with a hand-lever 20, mounted on the frame and arranged to move in a vertical plane. By the manipulation of the lever 20 the links 19 are actuated to move the plows 14 inwardly or outwardly to either the position shown in full lines in Fig. 1 or the position shown in dotted lines in said view. If they are carried toward each other to the position in the full lines in said view, it is evident 5 that as they are carried forwardly by the cable 13 they will scrape the gravel to the outside of the track. On the other hand, if they are adjusted to the position shown in dotted lines they will scrape the gravel between the 10 rails. It is evident that the plunger 11 and plows are drawn forwardly simultaneously, and as the plunger projects in front of the plows it will first unlock the tilting section 2 of the car and subsequently the operation of 15 the plows will effect the complete scraping of the gravel, as before described.

Having thus described the invention, what is claimed as new is—

1. The combination of a car provided in its 25 bottom with a central discharge-opening and two spaced-apart laterally-adjustable plows designed to be drawn over the bottom of the car on opposite sides of said opening.

2. The combination of a car provided in its 30 bottom with a central discharge-opening, a frame arranged to be drawn along the bottom of the car, and two plows hinged at opposite sides of said frame with their apexes free from attachment to each other and arranged 35 to be laterally adjusted, as and for the purpose set forth.

3. An unloading device for gravel-cars or the like comprising a frame designed to be drawn over the bottom of the car, two spaced- 40 apart laterally-adjustable plows carried by said frame, and means for holding said plows in different lateral positions with respect to each other, and means for drawing said frame over the bottom of a car.

4. An unloading device for gravel-cars or the like comprising a frame, means for drawing said frame over the bottom of the car, two angular plows hinged to said frame at opposite sides thereof with their front ends 45 free from connection with each other, and means connected with said frame for holding said two plows in different angular positions.

5. An unloading device for gravel-cars or

the like, comprising a frame designed to move over the bottom of the car, means for drawing said frame forwardly, two spaced-apart angular plows hinged at opposite sides of said frame at one end only, and means connected to the other end of each of said plows for adjusting the same laterally. 55

6. The combination with a car provided with a tilting discharge-section, of a plunger designed to be drawn over the bottom of the car and arranged to automatically unlock and tilt said section, and a scraping device 60 operatively connected with said plunger to move therewith, as and for the purpose set forth.

7. The combination with a car having a tilting bottom section of a frame designed to move over the bottom of the car and provided with a scraping device, and a plunger carried by said frame and extending beyond said scraping device and arranged to automatically unlock the said tilted section, as 75 and for the purpose set forth.

8. The combination with a car of the character described, embodying a tilted bottom section, of an unloading device comprising a frame, means for moving the frame over the 80 bottom of the car, laterally-adjustable plows carried by said frame and said plows being angular and means for holding said plows in different lateral positions with respect to the frame said means including a hand-operated 85 lever and links connecting the same with the plows and means for automatically unlocking and tilting said section in advance of the movement of the plows and frame in alignment with said section. 90

9. An unloading device for gravel-cars or the like, comprising a frame, two angular plows hinged at one end to opposite sides of said frame, links connected to the other ends of said plows and arranged to move said plows 95 laterally with respect to each other, and a hand-operated lever carried by said frame and connected to said links whereby to hold said plows in different angular positions with respect to each other. 100

In testimony whereof I affix my signature in presence of two witnesses.
